TELEPHONE BOOTH

Martin B. Schaffer, Park Forest, Ill., assignor to Acoustics Development Corporation, Park Ridge, Ill., a corporation of Illinois

Filed Nov. 8, 1961, Ser. No. 67,427

Term of patent 14 years

(Cl. D13—1)

fig.1.

fig.2.

fig.3.

fig.4.

fig.5.

FIGURE 1 is a front perspective view of a telephone booth showing my new design with the telephone shown in broken lines for illustrative purposes only,

FIGURE 2 is a front elevation of the telephone booth illustrated in FIGURE 1,

FIGURE 3 is a right end view of the telephone booth shown in FIGURE 1

FIGURE 4 is a back view of the telephone booth shown in FIGURE 1, and

FIGURE 5 is a bottom view of the telephone booth shown in FIGURE 1.

The top and left end of the telephone booth not shown are substantially plain and flat.

The dots shown in the interior of the booth in FIG-

URES 1 and 2 indicating acoustical material have been only partially shown for convenience of illustration only, it being understood that the dotted acoustical material continues throughout the adjacent plain areas shown to complete the interior pattern.

I claim:

The ornamental design for a telephone booth, as shown and described.
